CLAIM

The ornamental design for a fan motor, as shown and described.

DESCRIPTION

FIG. 1 is a perspective view showing our new design of a fan motor which may be used for cooling, for example, electronic circuits of personal computers, mobile telephones, and the like;

FIG. 2 is a top plan view thereof;

FIG. 3 is a front view thereof;

FIG. 4 is a bottom plan view thereof;

FIG. 5 is a rear view;

FIG. 6 is a right side view thereof; and,

FIG. 7 is a left side view thereof.
